CLAIM

The ornamental design for a desk lamp with wireless charging stand, as shown and described.

DESCRIPTION

FIG. 1 is a perspective view of a desk lamp with wireless charging stand showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the desk lamp with wireless charging stand where the desk lamp with wireless charging stand is in a configuration of use; and,

FIG. 11 is an exploded perspective view of the desk lamp with wireless charging stand.

The dash-dash broken lines in the drawings depict portions of the desk lamp with wireless charging stand that form no part of the claimed design.

1 Claim, 11 Drawing Sheets
